ELECTRICAL TRANSMISSION BANK

Waldo G. Rice, Chicago, Ill.

Application January 5, 1934, Serial No. 705,330

18 Claims. (Cl. 178—74)

This invention relates to electrical transmission devices and more particularly to relay devices for multiple telegraphic reception and distribution over multiplex circuits, although it 5 may be employed with equal advantage for other purposes.

It contemplates more especially the provision of electrical receiving relay banks having a comparatively low resistance or low energy drain 10 so that their multiple connection to telegraphic or similar electrical systems will not impair signal transmission or reception.

Methods and devices now used to accomplish multiple reception involve or require rather extensive revision of the distributor and/or printer connections as well as modifications of resistance values. This renders the installation expense of multiple reception and distribution prohibitive in that extensive modifications in resistance values and wiring of the original printer and/or distributor circuits. Except for isolated instances, multiple reception and distribution has not been practiced although there is a great and important need therefor. Relaying of messages 20 by manual reperforation for use with a transmitter at the receiving stations, is the substitute practice for automatic multiple reception and distribution which is expensive, involves much time, and entails additional labor which are factors that render multiple reception and distribution an important advance in electrical transmission and reception devices where such can be accomplished with equipment of the desired simplicity and flexibility and without entailing much time, expense or labor of installation.

For instance, the present invention provides for a simple, compact and inexpensive relay unit that can be connected between a distributor and printer in a multiplex setup by mere attachment 30 of suitable plug and socket complements to the cut ends of the six wire channel. The relay unit has similar leads terminating in corresponding plug and socket complements so as to afford ready and instantaneous connection between the printer and distributor. Similarly the relay unit or plate may be readily detached with the printer circuits restored to their original circuit setup by simply coupling together of the plug and socket previously attached to the severed wires of the 40 multiple channel.

It should be understood that in multiplex setups that utilize a cord and plug connection between the distributor receptacle and the printer plug, the intermediate relay unit or plate is attachable 50 by means of a cord terminating in an adapter

plug. The adapter plug is a complement of the regular cord and plug provided between the distributor receptacle and the printer plug, thereby offering instantaneous attachment and detachment of the relay unit. Reference has been 5 made to multiplex circuits, but the relay unit embodying the features of the instant invention, is likewise readily adaptable to simplex and duplex circuits operated on the start-stop method and employing printers provided with an independent 10 selector magnet for each selector circuit as commonly used on multiplex channels, thereby offering wide usefulness and general flexibility on various types of circuits for multiplex-reception.

One of the important features of this relay 15 unit or transmission bank is in the provision of relay coils of nominal or exceedingly low resistance values as compared with the regular printer coil and other resistances comprising the total resistance of each printer circuit usually 20 though not necessarily employing six coils in number. The relay armatures are instantaneously responsive to signal reception notwithstanding the low resistance of the coil windings. To this end, the relay coils are especially designed 25 to give a maximum number of turns on a minimum length of wire, thereby holding relay resistances to trivial values and yet secure the desired power of response that relays the signals without distortion or destroying accurate transmission, multiple reception and redistribution. On selector circuits operating 250 milliamperes, series connection of one relay-plate as described supra, will reduce the current intensity by approximately two milliamperes. Five plates connected in series would reduce current intensity by 30 about ten milliamperes which is still trivial in that such nominal variations leave unimpaired the wide marginal surplus provided for safe operation.

40 After extensive experimental work it was observed that when relays were mounted in compact proximity and especially when mounted on an iron base gains and losses of pulses developed as a result of magnetic inductive coupling between 45 adjacent relays. With a view of eliminating all tendency of chatter of the relay armatures as a result of the above referred to disturbances, a careful separation of the several relays and especially the avoidance of an iron mounting base 50 are purposely provided for in the design herein shown. By observing these precautions in design, special devices for locking in of the contacts commonly applied to the five selector armatures is rendered unnecessary, thereby adding to the sim- 55

5 plicity of operation and design. Known relay banks employ greater current intensities through the armature contacts, thereby requiring wider gaps due to fact that two or more circuits feed 10 through each contact. Furthermore, additional resistors and also condensers are required to overcome troublesome sparking tendencies. This is avoided in the present relay-plate by confining the selector relays to the operation of a single 15 printer coil unit, this further adding to the simplicity and dependability of the present invention.

10 One object of the present invention is to provide a relay plate having coils of comparatively low resistance values or energy drain that avail 15 the multiple connection of relay units to a channel without impairing signal transmission and/or reception and/or redistribution.

15 Another object of the present invention is to simplify the construction and improve the operation 20 of singleplex and/or multiplex circuits for effecting multiple distribution or re-distribution of electrically transmitted signals.

20 Still another object is to provide an electrical transmission bank of exceedingly low energy 25 drain so that their connection in multiple units to a system will not impair signal transmission and reception over a simplex, duplex or multiplex system for effecting redistribution over a plurality of signal transmitting channels.

25 30 A further object is to provide a simple device that enables the ready incorporation of additional printers and/or reperforators in any electrical transmission channel without the necessary modification of electrical circuits, resistance values or wiring changes in the original printer, distributor or reperforator connections.

30 35 A still further object is to provide a simple, compact and self-contained relay unit of such low energy drain so that single or multiple units may be readily incorporated without operation impairment 40 in the receiving circuit of a signal transmission channel so as to afford multiple reception and redistribution without entailing any appreciable expense, time or labor.

40 45 Still a further object is to provide a relay having coils of nominal resistance values or low energy drain with sensitively mounted coil armatures that respond to all variations in signal impulses for multiple reception and redistribution.

45 50 Other objects and advantages will appear from the following description of an illustrated embodiment of the present invention.

50 In the drawings:

55 Figure 1 is a plan view of a relay plate or transmission bank embodying features of the present invention.

Figure 2 is a sectional view taken substantially along line II—II of Figure 1.

60 Figure 3 is a sectional view taken substantially along line III—III of Figure 1.

Figure 4 is a sectional view taken substantially along line IV—IV of Figure 1.

Figure 5 is a sectional view taken substantially along line V—V of Figures 1 and 3.

65 Figure 6 is a perspective view of a relay coil armature showing an assembled association in Figures 1, 3, and 4.

70 Figure 7 is a plan view of an adaptor terminal plate for detachably receiving a relay plate to effect instantaneous electrical connection to the circuit.

Figure 8 is a sectional view taken substantially along line VIII—VIII of Figure 7.

75 Figure 9 is a conventional wiring diagram of the relay plate showing its connection to a dis-

tributor, there being a conventional showing of the plug for connection to the next printer.

Figure 10 is a conventional wiring diagram of the relay plate showing connections to a printer and distributor through adaptor plugs and sockets so as to enable instantaneous connection to any type of system now in use.

80 The structure selected for illustration comprises a bottom plate 10 which is of square or rectangular configuration and preferably though not essentially of non-magnetic material such as bakelite or other insulating composition. In this instance, another plate 11 is disposed above the bottom plate 10, it being of similar size, shape and composition for spaced parallel support by a plurality of studs 12 which have lock nuts 13 with spacer collars 14 disposed therebetween to rigidly maintain the bottom and base plates 10 and 11 in spaced parallelism. The spaced parallel bottom and base plates 10 and 11 serve to receive the 20 wiring therebetween for connection to the instrumentalities to be hereinafter described.

85 A bank of relays 15, in this instance six, are mounted on the base plate 11 in lateral alignment proximate to an edge thereof. Each of 25 these relays consists, in this instance, of two low energy drain coils 16 and 17 that have core rods 18 with threaded ends 19 receiving nuts 20 and 21 on either side of the base plate 11 which serves as a support therefor. The top extremities of the 30 core rods 18 have nuts 22 and 23 in threaded engagement therewith to receive a substantially rectangular top plate 24 of insulation material therebetween to support the relay armature 25 as will appear more fully hereinafter. It is to 35 be noted that flanged cylindrical sleeves 26 provided with exterior surface insulation, envelop the core rods 18 intermediate the lock nuts 20 and 22 which engage the base plate 11 and top relay plate 24. Lock nuts 20 and 21 also retain 40 soft iron yokes or plates 20' and 21' connected to the core rods 18 on both sides of the base plate 11. The sleeves 26 serve to sustain the coils wound over the peripheral insulating surfaces thereof with enameled copper wire to define 45 spiral convolutions 27.

45 50 The low energy drain coils 16 and 17 preferably though not essentially are wound from number twenty-six (26) copper enameled wire that have a resistance of 40.2 ohms per 1000 feet. 55 Each coil comprises substantially forty six feet or a resistance of 1.85 ohms per coil which is equal to 3.7 ohms for both coils 16 and 17 of each relay. These coils are specially designed to give a maximum number of turns on a minimum length of wire, thereby maintaining relay resistances to nominal or negligible values and still secure the desired power of response that customarily was thought to require relay resistances approximating one hundred forty ohms in single- 60 duplex and multiplex receiving circuits on electrical signal transmission channels. Consequently, a large number of relay plates of the type described supra may be connected in series in a printer and/or perforator and/or reperforator circuit or circuits for automatic multiple redistribution of messages to different stations without impairing the marginal current intensity surplus provided for safe operation of electrical transmission and reception signal devices. The 65 low energy drain characteristics of the coils 16 and 17 can also be approximated by having high resistance coils with connections that provide a leak to the ground.

65 70 Now, then, the relay armature 25 is, in this 75

instance, of key configuration (Figure 6) so as to present transversely aligned ears 28 and 29 with an intermediate ear 30 along the longitudinal median line of the elongated armature shank 31. The aligned ears 28 and 29 are provided with depending pins 32 for registry with apertures 33 provided in a transversely disposed plate 34 fixed to the relay top plate 24 by means of a threaded stud 35. The top plate 24 serves as a support for the armature pins 32 which is a fulcrum for the relay armature 25. This arrangement provides a sensitive mount for the armature 25 which will respond to slight electrical impulses and be capable of delicate adjustment. An enlarged aperture 36 in the armature 25 enables access to the plate securing stud 35 by means of a screw driver for adjustment purposes.

The armature 25 is longitudinally slotted as at 36 to frictionally retain a contact screw 37 in a threaded aperture provided for that purpose. The contact screw 37 confronts a contact terminal 38 mounted on the extremity of the top relay plate 24 for connection through a wire 39 to a tubular terminal jack 40 provided in a plug 41. The plug 41 has sufficient terminal jacks 40 for lead wires 39 coming from each of the armature contact terminals 38 on the bank of relays 15, there being additional terminals in the plug 41 as will appear more fully hereinafter. A coil spring 42 is anchored to a nut 43 in threaded engagement with an elongated stud 44 which extends upwardly through the base plate 11 for attachment by means of a nut 45 in engagement therewith. A lock-nut 46 engages the spring adjusting nut 43 to preclude the accidental displacement thereof so that the tension in the spring 42 will not vary unless adjusted.

A rod 47 extends from the spring 42, it having the free extremity thereof provided with an enlarged head 48 for lodgment in an aperture 49 through a slotted lateral opening 50. The spring 42 normally urges the relay armature 25 in a counterclockwise direction (viewed from Figure 4) so as to effect the separation of the screw 37 from its contact 38 when the relay coils 16 and 17 are de-energized. An adjustable limit stop screw 51 threadedly engages a slotted plate 52 supported above the armature 25 by a block 53 which is attached to the relay top plate 24, thereby precluding undue receding movement of the armature 25 from its contact 38. A spring plate or latch 54 is pivoted as at 55 to the armature 25 so as to engage the coiled spring extension rod extremity 48 for retention in the armature aperture 49 against accidental displacement through the slot 50 (Figure 6) and to insure a firm electrical connection. The convolutions 27 that are wound around the peripheral surfaces 26 of the cores 18 are connected so that the coils 16 and 17 of each relay 15 are in series with lead wires 56 and 57 constituting terminals of both coils 16 and 17, respectively, for projection through the base plate 11. The bottom core nuts 21 which are in threaded connection with the core rods 18, serve to anchor the terminals of wires 56 and 57 of the coils 16 and 17. The lead wires 56 and 57 are disposed between the bottom plate 10 and base plate 11 for connection to terminal jacks 58 and 59 carried by plugs 60 and 61, respectively.

It is to be noted that the lead wires 56 are in electrical connection with terminal pins while the lead wires 57 are in electrical connection with tubular jacks 59 that are complementary to each other in conventional plugs 60 and 61 for

telescopic engagement with corresponding opposite plug sections extending from the secondary distributor and printer as will appear more fully hereinafter. A small ammeter 62 is mounted on the base plate 11 for rapid and precision adjustment of the armatures 25 of the relays 15. The ammeter terminals 63 and 64 are in circuits with the resistors 65 and 66 through pin jacks 67, 68, and 69 mounted on the base plate 11. Interchanging the pin jacks 67 and 68 reverses the current through the meter 62 when a negative battery is employed in connection with the power source leads 70 and 71 which are in circuit with the relay contacts 38. Additionally, leads 70 and 71 are connected to the tubular jacks 72 and 73 provided in conjunction with the relay terminal contact jack 40 in the plug 41 (Figure 9) for furnishing power to the standard secondary printer and/or reperforator. Insertion of the pin jack 69 shunts out meter 62 when not used for adjustment purposes so that it is selectively incorporated in the relay circuits.

Another pair of pin jacks 74 and 75 are provided on the base plate 11 in the relay circuits, the relays 15 being so grouped that resistance 25 65 is in circuit with the single sixth pulse relay 15 (extreme right in Figure 1 and extreme left in Figure 9) while resistance 66 serves the remaining five selector relays 15 which operate the selector magnets on the secondary printers and/or reperforators. These resistances 65 and 66 have an approximate resistance of 300 and 400 ohms and serve to determine the current flow through the relays 15. Now, then, by interchanging the pin jacks 74 and 75 (Figure 9) the meter 62 will be transferred from the sixth pulse relay 15 to the bank of five selector relays 15 for adjustment of the relay armatures 25 thereon. A manual switch 76 is mounted on the base plate 11, it being in the battery circuit to enable the disconnection of the power source from the relay contacts 38 and motor or solenoid that operates the secondary printer and/or reperforator.

In short, this switching arrangement through pin jacks 67 and 68 reverses the direction of current passing through the ammeter 62 when a negative battery constitutes the power source.

The single jack plug 69 is provided for shunting off the current through ammeter 62 when not being used for adjustment purposes. The switching 50 arrangement through jack pins 74 and 75 is also provided for transferring the ammeter 62 from the five selector relay circuits to the six pulse relay circuit so that a single ammeter serves both the selector and operating circuits for testing all 55 armature adjustments. To adjust the relay armatures 25, the tensions of the springs 42 are set, in this instance, for one ounce tension and permanently locked in position by lock-nuts 46 and not disturbed thereafter. When the relay plate 10—11 is operated on a multiplex channel—the channel is first set up as for local operation, the first pulse locked in at the transmitter. The pulsating deflection of the milliammeter pointer 62 is then noted. Should the pointer deflection be 65 insufficient or less than an arbitrary reading of 125 milliamperes on the scale, then the contact screw 37 on the armature 25 is turned in a counterclockwise direction to close the air gap between the magnet core ends 22—23 and armature 25. If the deflection is too great, the contact screw 37 is turned in a clockwise direction, thereby lifting the armature 25 away from the core ends 22—23 until the ammeter pointer deflection is at 125 on the meter 62. Similarly, the 75

adjustment is made on each of the five selector armatures 25. The six pulse armature 25 adjustment may be made at this time by switching the meter 62 into the sixth pulse circuit so that similar 5 adjustment can be determined and made as before. However, the sixth pulse adjustment may be made at any time when the multiple channel is ready for actual operations. On stop-start keyboard distributors, adjustment is made by operating 10 the various pulses singly by pressing down the key board distributor corresponding to each single pulse that is being adjusted. The air gap of the contacts is determined by gradually closing the back stop armature screw 51 until the contact screw 37 closes the gap or touches the contact 15 38 as noted on the meter swing to 250. The screw 51 is then turned in a counter-clockwise direction for one quarter turn to procure the proper contact-gap adjustment.

20 The plate 11 is also provided with an exteriorly accessible cord 17 constituting an extension of the switch 76 for the purpose of disconnecting the battery from the relay contacts 38 and the power to the secondary printer motor or 25 solenoid coil. The cord extension 17 is used when the relay plate 10-11 is completely confined by a housing 78 with its telescopically engaged closure 79 so as to preclude access to the switch 76 for accomplishing the same purpose. It is to be 30 noted that the first five relays 15 (viewed from the left in Figure 1 or from the right in Figure 9) are the selector relays which close the selector circuits for operating the selector magnets in the telegraphic printers and/or reperforators of 35 standard or known construction. The sixth relay 15 (extreme right in Figure 1 and extreme left in Figure 9) transmits the pulse to the magnet or relay of the printer or reperforator (not shown) that initiates operation of the main shaft of the power instrumentalities thereof through a magnet or other actuator that is now or in the future 40 may be employed on telegraphic printing or reperforating equipment.

45 This relay action is accomplished by connecting (plug 41 to the standard secondary printer or reperforator which is provided with a complementary plug attachment therefor) relay-plate plug 60 through its pin jacks 58 to the complementary tubular jacks 80 provided in a plug body 81 (Figure 9) which have lead wires 82 connected to a standard telegraphic distributor 83. Then, too, the plug body 61 through its tubular jacks 59 is connected with complementary pin jacks 84 provided in a plug body 85 which have lead wires 50 86 connected to the standard primary printer 87, thereby placing the printer coils 88 in circuit with the relay coils 27 so that the desired number of additional secondary printers and/or reperforators may be placed in series through relay 55 plates 10-11 by establishing connection with their respective plugs 41 to function simultaneously with the primary printer and/or reperforator. This same circuit connection of the relay plate 10-11 with the primary distributor 83 and printer 60 87, is shown in Figure 10 having a double adaptor plug 89 and 90 which establish detachable connection with the distributor 83' and printer 87' rather than resort to permanent tapping of wires 82 and 86 with the distributor 83 and primary printer 87 as shown in Figure 9. The double adapter plug 89-90 is used wherever primary printers or reperforators have cord and plug connections with the distributor as standard equipment.

65 75 This relay-plate 10-11 with the wiring ar-

rangements afford any desired number of message copies at one receiving station or permits the automatic transmission of the same message by means of reperforated copy to any number of different stations through tape transmitters or 5 by printer extensions to local or even remote locations. For each additional secondary printer or reperforator that produces a tape copy, a relay-plate 10-11 of the type described supra may be incorporated into the distributor or primary 10 printer circuit so long as the additional resistance thereof will not impair the operating margin of the current intensity required for the primary printer and/or reperforator and/or for the added secondary printers and/or reperforators. The 15 feature of trivial resistance values in the relay-plate or bank design embodying features of the present invention, is of primary importance in that the series connection of a large number of the above described relay-banks to distributor 20 circuits have proven successful. Trivial resistance values are made possible in a large measure by the precision adjustment afforded by the test ammeter 62 and the sensitive mounting of the relay armatures 25 which enables the use of low re- 25 sistance relay coils 27.

Where standard relay plates with a connecting frame are already in use, the plugs 60 and 61 with their lead wires 56 and 57 may be dispensed with, and exposed terminals 91, in this instance 30 sixteen, are provided in linear alignment proximate to an edge 92 of the base plate 11. To that end, the relay coil leads 56 and 57 are connected to the exposed terminals 91 which are designed to cooperate with resilient slip contacts 93 35 mounted on an insulator block 94 constituting a part of a standard connecting frame 95. The slip contacts 93 are so spaced upon the block 94 as to correspond with the arrangement and spacing of the relay-plate terminals 91 so that 40 their exposed heads will be in frictional contact therewith responsive to complementary association therebetween. This is effected by merely sliding the relay plate 10-11 into position on the connecting frame 95 with the relay-plate housing 45 78-79 removed or entirely dispensed with. The slip contacts 93 have lead wires 82 and 86 connected thereto for attachment to the block 94, thereby establishing a series connection with the primary distributor 83 and printer 87 having the 50 relay coils 27 in circuit therewith in the manner described in connecting with the plugs 60 and 61, supra. By resort to the connecting frame 94, the relay-plate 10-11 may be utilized without 55 any special plugs or other described connections, except for the plug 41 which establishes connection with the secondary printer and/or reperforator.

Various changes may be made in the embodiment of the invention herein specifically described 60 without departing from or sacrificing any of the advantages of the invention as defined in the appended claims.

I claim:

1. In a transmission bank for connection to the distributor of a telegraphic system or the like, the combination with a plurality of selector pulse circuits for connection to the coils of a primary receiving unit, of a power pulse circuit 70 for connection to the actuator coil of the primary receiving unit, relays having low energy drain coils in said selector and power pulse circuits, and a plurality of secondary circuits for conveying the pulses of said selector and power pulse relays 75

- to a secondary receiving unit for duplicate redistribution of the signals received by said primary receiving unit without appreciable current drain.
5. In a transmission bank for connection to the distributor of a telegraphic system or the like, the combination with a plurality of selector pulse circuits for connection to the coils that initiate the selective action of a primary receiving unit, of a power pulse circuit for connection to the actuator coil that operates the mechanical mechanism of the primary receiving unit, relays having low energy drain coils in said selector and power pulse circuits for operation without appreciable drain, and a plurality of secondary circuits connected to the relay armature contacts for conveying the pulses of said selector and power pulse relays to a secondary receiving unit for duplicate recordation of the signals received by said primary receiving unit.
3. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays having low energy drain coils in said selector and power pulse circuits for operation without appreciable drain and a plurality of secondary circuits for conveying the pulses of said selector and power pulse relays to a secondary receiving unit for duplicate redistribution of the signals received by said primary receiving unit, said relays having coils of a resistance less than the resistance of the receiving unit to avoid impairment to the safety margin of operation of said primary receiving units.
4. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays having low energy drain coils in said selector and power pulse circuits for operation without appreciable drain, and a plurality of secondary circuits for conveying the pulses of said selector and power pulse relays to a secondary receiving unit for duplicate redistribution of the signals received by said primary receiving unit, said relays having coils of such low drain characteristics that they do not impair the safety margin of operation of said primary receiving units.
5. In a transmission bank, the combination with a plurality of relays having low energy drain coils, of a corresponding number of primary pulse circuits including the coils of said relays for operation without appreciable current drain, a corresponding number of secondary circuits extending from the armature contacts of said relays and plug connectors having terminal jacks for receiving the ends of said primary and secondary circuit wires, said plug connectors establishing detachable connection of said pulse and secondary circuits with a telegraphic distributor constituting a primary receiving unit, and secondary receiving unit for message duplication or redistribution responsive to the operation of said relays without appreciable current drain.
6. In a transmission bank, the combination with a plurality of relays having low energy drain coils, of a corresponding number of primary pulse circuits including the coils of said relays, a corresponding number of secondary circuits extending from the armature contacts of said relays and plug connectors having terminal jacks for receiving the ends of said primary and secondary circuit wires, said plug connectors establishing detachable connection of said pulse and secondary circuits with a telegraphic distributor constituting a primary receiving unit, and secondary receiving unit for message duplication or redistribution, one of said primary and secondary pulse circuits serving as a power pulse circuit for actuating the instrumentalities of said primary and secondary receiving units responsive to the operation of said relays without appreciable current drain.
7. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays in said selector and power pulse circuits, a plurality of secondary circuits for conveying the pulses of said selector and power pulse relays to a secondary receiving unit for duplicate redistribution of the signals received by said primary receiving unit, said relays having coils of such low drain characteristics that they do not impair the safety margin of operation of said primary receiving units with a plurality of secondary units in circuit therewith, and a current meter for connection to said circuits for testing the relay armature adjustments.
8. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays in said selector and power pulse circuits, a plurality of secondary circuits for conveying the pulses of said selector and power pulse relays to a secondary receiving unit for duplicate redistribution of the signals received by said primary receiving unit, said relays having coils of such low drain characteristics that they do not impair the safety margin of operation of said primary receiving units with a plurality of secondary units in circuit therewith, a current meter for connection to said circuits for testing the relay armature adjustments, and means for switching said meter into said selector or power pulse circuits.
9. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays having low energy drain coils in said selector and power pulse circuits, pin-shaped means for pivotally sustaining said relay armatures, and a plurality of secondary circuits for conveying the pulses of said selector and power pulse relays to a secondary receiving unit or units for operation without appreciable current drain for duplicate redistribution of the signals received by said primary receiving unit.
10. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays in said selector and power pulse circuits, a plurality of secondary circuits for conveying the pulses of said selector and power pulse relays to a secondary receiving unit or units for operation without appreciable current drain for duplicate redistribution of the signals received by said primary receiving unit.

- 5 pulse circuits, pin-shaped means for pivotally sustaining said relay armatures, said relays having low energy drain coils for operating said armatures without appreciable current drain, and a plurality of secondary circuits for conveying the pulses of said selector and power pulse relays to a secondary receiving unit for duplicate redistribution of the signals received by said primary receiving unit.

10 11. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays in said selector and power pulse circuits, pin-shaped means for pivotally sustaining said relay armatures, said relays having low energy drain coils for operating said armatures without appreciable current drain, tension springs for normally urging the relay armatures to one extreme limit of movement, and a plurality of secondary circuits for conveying the pulses of said selector and power pulse relays to a secondary receiving unit for duplicate recordation of the signals received by said primary receiving unit.

15 12. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, relays in said selector and power pulse circuits, pin-shaped means for pivotally sustaining said relay armatures, said relays having low energy drain coils of low resistance values for operating said armatures without appreciable current drain, tension springs for normally urging the relay armatures to one extreme limit of movement, means for adjusting the tension in said spring, and a plurality of secondary circuits for conveying the pulses of said selector and power pulse relays to a secondary receiving unit for duplicate redistribution of the signals received by said primary receiving unit.

20 13. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said selector and power pulse circuits, pin-shaped means for pivotally sustaining said relay armatures, an apertured plate fixed to said relay for freely receiving said pin-shaped armature sustaining means, and a plurality of secondary circuits for conveying the pulses of said selector and power pulse relays to a secondary receiving unit for duplicate recordation of the signals received by said primary receiving unit.

25 14. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said selector and power pulse circuits, pin-shaped means for pivotally sustaining said relay armatures, an apertured plate fixed to said relay for freely receiving said pin-shaped armature sustaining means, limit means for adjusting the armature gap of said relays, and a plurality of sec-

30 15. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said selector and power pulse circuits, pin-shaped means for pivotally sustaining said relay armatures, an apertured plate fixed to said relay for freely receiving said pin-shaped armature sustaining means, limit means for adjusting the armature gap of said relays, said relays having coils of low resistance values for operating said armatures without appreciable current drain, and a plurality of secondary circuits for conveying the pulses of said selector and power pulse relays to a secondary receiving unit for duplicate redistribution of the signals received by said primary receiving unit.

35 16. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said selector and power pulse circuits, pin-shaped means for pivotally sustaining said relay armatures, an apertured plate fixed to said relay for freely receiving said pin-shaped armature sustaining means, limit means for adjusting the armature gap of said relays, said relays having coils of low resistance values for operating said armatures without appreciable current drain, a plurality of secondary circuits for conveying the pulses of said selector and power pulse relays to a secondary receiving unit for duplicate redistribution of the signals received by said primary receiving unit, and a meter connection to said circuits for testing the relay armature gap adjustments.

40 17. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said selector and power pulse circuits, pin-shaped means for pivotally sustaining said relay armatures, an apertured plate fixed to said relay for freely receiving said pin-shaped armature sustaining means, limit means for adjusting the armature gap of said relays, said relays having coils of low resistance values for operating said armatures without appreciable current drain, a plurality of secondary circuits for conveying the pulses of said selector and power pulse relays to a secondary receiving unit for duplicate redistribution of the signals received by said primary receiving unit, a meter connection to said circuits for testing the relay armature gap adjustments, and means for switching said meter into said selector or power pulse circuits.

45 18. In a transmission bank for connection to the distributor of a telegraphic system or the like, the combination with a plurality of selector pulse circuits for connection to the coils of a primary receiving unit, of a power pulse circuit for connection to the actuator coil of the primary receiving unit, low energy drain relays in said se-

lector and power pulse circuits, pin-shaped means for pivotally sustaining said relay armatures, an apertured plate fixed to said relay for freely receiving said pin-shaped armature sustaining means, limit means for adjusting the armature gap of said relays, said relays having coils of low resistance values for operating said armatures without appreciable current drain, a plurality of secondary circuits for conveying the pulses of

5
10 said selector and power pulse relays to a sec-

ondary receiving unit for duplicate redistribution of the signals received by said primary receiving unit, a meter connection to said circuits for testing the relay armature gap adjustments, means for switching said meter into said selector or power pulse circuits, and means for reversing the current flow through said testing meter when a negative power source is connected to said circuits.
